APPARATUS FOR EDGE-GLUING STRIP ELEMENTS

Paul H. Bilhuber, Douglas Manor, N. Y., assignor
to Steinway & Sons, New York, N. Y., a corpora-
tion of New York

Application September 10, 1943, Serial No. 501,792

3 Claims. (Cl. 144—279)

1

This invention relates to the edge-gluing of strip elements such, for example as lumber-core stock for lumber-core plywood, solid dimension stock for chair seats, solid tops, piano soundboards, etc., and veneers and to the apparatus therefor and relates more particularly to the continuous-feed edge-gluing of elements of the nature aforesaid and to the apparatus therefor.

Objects and advantages of the invention will be set forth in part hereinafter and in part will be obvious herefrom, or may be learned by practice with the invention, the same being realized and attained by means of processes, steps, instrumentalities and combinations pointed out in the appended claims.

The invention consists in the novel steps, methods, procedures, parts, constructions, arrangements, combinations and improvements herein shown and described.

The accompanying drawings, referred to herein and constituting a part hereof, illustrate one embodiment of the invention, and together with the description, serve to explain the principles of the invention.

Edge-gluing of lumber boards or other strip elements using thermo-setting adhesives, by means of so-called continuous-feed presses is well known. In such operations, the elements issue from the press as a continuous ribbon of elements in edge-joined relationship. In order to set the adhesive along each "glue line" the press is provided with hot plates or surfaces which bear upon and heat the elements as they are intermittently advanced therebetween by strokes of a lever at the feed end of the press. Such presses are characterized by an excess length consequent upon the length of heating surface required for a favorable rate of production of a ribbon or panel having glue joints of strength adequate to permit handling without fracture as it issues from the press.

The present invention has among its objects to enable the continuous-feed edge-gluing of strip elements to be carried out in a more rapid, facile and efficient manner and with equipment which will require less space.

In the accompanying drawings which form part of the instant specification and are to be read in conjunction therewith and in which like numbers refer to like parts throughout the several views:

Fig. 1 is a partly fragmentary view in side elevation with parts in section of a typical and illustrative embodiment of continuous-feed, edge-joining apparatus in accordance with this invention suitable for carrying out the method of this invention;

2

Figs. 2 and 3 are sections taken along the lines 2—2 and 3—3 respectively of Fig. 1;

Fig. 4 is a fragmentary view in perspective of a panel structure such as is produced by the apparatus of Fig. 1; and

Fig. 5 is a view in perspective of a modified form of electrode as applied to edge-gluing in accordance with this invention.

To the accomplishment of the foregoing ends 10 and objects and in accordance with this invention, there is provided a platform or table structure having at one end cyclic feeding mechanism for advancing a strip element treated with adhesive from one to the other of a pair of stations at the feed end of the platform.

The operating cycle of the feeding mechanism is preferably such as to provide a dwell or rest period between successive feeding periods thereby to enable the operator to position a fresh strip in the

20 first or feed station following movement of the preceding strip to the second station of the pair. As each fresh strip, adhesively treated along one edge, is moved by the feeding mechanism from the first to the second station of the pair, it will move

25 the preceding strip with a firm pressure from the second station along and toward the other end of the platform or table. The addition of fresh adhesively treated strips may be continued until the assembly of strips has attained the desired length.

30 The several strips are treated with adhesive preferably prior to being placed in the feed station, so that a layer of adhesive will be interposed in the joint between successive strips and means are provided for electrostatically heating each joint for a predetermined period of time as the strips advance along the platform. To this end, the platform is provided intermediate its ends with one of a pair of electrodes in an ultra high frequency circuit, the other electrode being positioned in suitably spaced overlying relation thereto so as to provide a high frequency electrostatic field through which the strip assembly passes in transit along the platform. Under these conditions, the "glue-joint" between each pair of elements will be

35 parallel or substantially parallel to the electrostatic field and the adhesive, which is preferably one of the so-called cold-setting liquid resin glues, for example, of the urea formaldehyde or phenolic type whose curing is accelerated by heat and the

40 addition of a suitable catalyst, will be heated to the required temperature, set and caused to develop its full strength, substantially instantly. This is in marked contrast to the extended time required to obtain the same strength with conventional cold-press or hot-press edge-gluing prac-

45

tices. Because of the rapidity with which the heating is accomplished, the electrostatic field may be relatively short with material saving in length of apparatus over the conventional continuous-feed hot-press equipment.

In order to ensure the obtainment of a tight joint between each pair of strip elements, means are provided for resiliently adjustably mounting at least one of the electrodes so that they may be made to offer more or less constant frictional resistance to the passage of the strip assembly therebetween. Thus, by decreasing the height of the expansible inter-electrode passage, a greater pressure will be required to overcome the frictional resistance offered by the electrodes and hence each strip element may be made to exert a greater pressure on its preceding element. At the same time, the pressure between successive elements will be maintained at the desired level during heating of the joint and until the joint issues from the inter-electrode passage-way.

It will be understood that the foregoing general description and the following detailed description as well are exemplary and explanatory but are not restrictive of the invention.

Referring now more particularly to the embodiment of this invention shown in the accompanying drawings, a platform 10 offering a smooth, table-like top surface 11 carries at one end a ram 12 overlying the top surface 11. The front or working face 13 of the ram 12 is preferably planar and normal to the top surface 11 so as to engage uniformly a work piece 14 and is preferably coextensive or substantially coextensive in width with the top surface 11. A narrow footing 15 at the front of the ram slidably engages the top surface 11 of the platform, the ram being spaced from the surface 11 rearwardly of the footing to minimize friction. At the back of the ram is a rod 16 which traverses the ram interiorly transversely of the platform. The rod 16 extends at its ends from either side of the ram into a pair of slotted guide members 17, one at each side of the platform, each having a slot 18 therein for the purpose provided. The guide members 17 are anchored in any suitable fashion to the platform 10 as to which they and the slots 18 extend longitudinally so as to confine the ram 12 to a limited longitudinal path of movement along the surface 11.

A pair of cam operated levers 20, one at each side of the platform 10 are carried by a shaft 24 to which they are attached at either end by means of a pair of hubs 21 journalled in a pair of bearing members 22 in turn carried by a pair of platform legs 23, one at each side of the platform.

The respective levers 20 are provided at the top with a slot 25, the rod 16 being lodged at opposite ends in the respective slots. Spring means 26 provided at the bottom of each lever normally yieldably oppose clockwise movement thereof, as viewed in Fig. 1.

A pair of cam members 30, one at each side of the platform, are carried by a shaft 31 to which they are attached at either end, the shaft 31 in turn being journalled adjacent its ends in a pair of bearings 32 secured to frame members 33 of the platform supporting structure.

A pulley 34 fixed to the shaft 31 is adapted to be driven by means of a suitable prime mover (not shown) to which the pulley is connected as by means of a belt 35.

The cam members 30 respectively engage one

of a pair of cam followers 36 carried by the levers 20 and are suitably contoured so that in a full revolution from the position shown in Fig. 1, the ram 12 will be caused to remain at rest for part of the revolution, will then be advanced to the right to the full limit of its stroke and then be returned to its starting position by the spring means 26.

A pair of high frequency sheet metal electrodes 10 and 41 are positioned intermediate the platform ends so as to receive therebetween the strip elements as they are successively advanced by the cyclical operation of the ram 12. The electrodes are connected in suitable fashion in an ultra high frequency electrical circuit powered by a suitable high frequency generator 42 diagrammatically indicated in Fig. 1.

The electrodes 40 and 41 are preferably substantially coextensive in width with the platform 10 so as to extend the full length of the joint between successive strip elements passing therebetween. They extend lengthwise of the platform a distance sufficient to provide the necessary time element for the desired heating effect, their length being thus dependent to a measurable extent upon the average rate of travel of the strip elements therebetween, as will be apparent to those skilled in the art.

The electrode 40 may be a coating of copper or 30 other suitable electrode material applied to the platform surface 11 in which case the electrode portion may be insulated from the platform portions on either side thereof. Or the electrode 40 may be insulated from the platform 10 as a whole 35 in any suitable fashion. As here preferably embodied, the electrode 40 is set into the platform 10 so as to lie flush therewith, and offer no obstruction to movement of the strip elements 14 thereover. The platform 10 in such case is constructed of wood or a material having suitable insulating, i. e. dielectric properties.

The electrode 41 is preferably a thin sheet of aluminum, copper or other suitable metal having a turned-up edge 43 providing with the platform 10 a converging mouth facilitating the entry of the workpiece 14 thereinto and means are provided for resiliently adjustably mounting the electrode 41 in spaced relation to the platform 10 and the platform electrode 40 so as to provide an adjustable expansible passage between the electrodes. To this end, and as here preferably embodied the electrode 41 is secured to a number of rails 44 of wood or other suitable insulating material, extending lengthwise of the platform and in parallel relation to each other. Each of the rails 44 is provided at either end with a threaded guide rod 45 extending vertically upwardly therefrom, the front and rear sets of rods 45, as viewed in Fig. 1, passing 50 through front and rear supporting structures 46 vertically adjustably mounted on the platform 10.

The guide rods 45 are each provided with a coil spring 47 concentric therewith and extending 65 between the related structure 46 and rail 44, the springs 47 serving to urge the rails 44 toward the platform 10. Adjusting units 48 carried by the rods 45 and coacting with the related supporting structure 46 are provided for limiting the 70 extent of downward movement of the rails 44 and hence provide a means for controlling the pressure exerted by the electrode 41 on the strip elements 14. In order to accommodate strip elements of different thicknesses between the electrodes, means are provided for vertically ad-

justably mounting the respective supporting structures 46 on the platform 10, which means may be any suitable mechanical arrangement enabling vertical adjustment of the frameworks 46 as a unit. As here preferably embodied, studs 49 pass through vertical slots 50 in the opposite side rails 51 of the respective structures 46, into releasable engagement with the platform 10 at either side thereof.

In the operation of the depicted embodiment of this invention, the operator places a work piece 14 on the platform 10 against the ram 12 while the latter is at rest in its retracted position. The front face, that is, the bonding faces, of each succeeding strip element may be coated at this time with adhesive. Preferably, however, treating of a strip element with adhesive is carried out beforehand in any suitable fashion. The work piece 14 is now advanced automatically by operation of the cams 30, into the space between the high frequency electrodes 40 and 41, the inter-electrode space having been adjusted to the thickness of the strip element and the pressure exerted by the spring pressed "hold-down" electrode 41 normal to the strip element 14 having been established by suitable adjustment of the adjusting nuts 48. The pressure established is preferably just sufficient to cause the succeeding strip element as it is advanced by the ram 12, to exert a firm pressure on the preceding element uniformly over the joint surface and to maintain this pressure as the ram retreats to the first or feeding position. Thus, as the strip elements are advanced into and along the passage between the electrodes 40 and 41 a firm pressure will be exerted and maintained between each pair of electrodes at the bonding surface until the strip elements exist from the inter-electrode passage. During the intermittent advance of the successive strip elements along the inter-electrode passage, an ultra-high frequency electrostatic field is maintained between the electrodes by means of the high frequency generator. This field is of sufficient intensity, considering voltage, frequency and capacitance, to heat the adhesive in each joint to a setting temperature and to develop substantially the maximum strength of the adhesive during the relatively short transit period of each joint as it advances in intermittent fashion along the passage. Because of the firm pressure maintained at the joint during transit and the preferential heating of the adhesive because of its high dielectric constant, the elements are firmly bonded to each other and the adhesive substantially full set in a very short space of time. The elements issue from between the electrodes as a continuous ribbon or panel structure such, for example, as is depicted in Fig. 4. This structure may be cut to any desired length and since full setting of the adhesive is accomplished or substantially accomplished within the limits of the relatively short electrodes 40 and 41, the device lends itself to use in places of limited floor space in which the conventional edge-gluing apparatus could not be employed.

It will be understood that apparatus of the nature aforesaid lends itself readily to the edge-gluing of strip elements of different size. In general, wooden boards or other strip elements of a thickness in the range $\frac{1}{4}$ " to 2", a width in the range 3" to 8" and any suitable length commensurate with the width of the electrodes, are representative of strip elements suitable as

raw material for the production of unitary panel structures in accordance with the present invention. Obviously elements different in length and/or width, where thickness is the same, may be employed. With electrodes in the order of one foot in length, that is, in the direction of motion of the strip elements, satisfactory edge joining of such strip elements may be attained when employing a frequency of, for example, in the order of two (2) megacycles, a voltage of from 2000 to 3000 volts and a power input in the order of one (1) kilowatt to the electrodes. A transit time of around fifteen (15) seconds will generally be found more than sufficient under these conditions to develop the maximum strength of the adhesive without noticeable heating of the wood. A materially great increase in production rate is thus made possible.

Instead of employing a pair of electrodes such as the electrodes 40 and 41 of Fig. 1, the upper electrode may consist of a strip 52 of sheet metal, Fig. 5, say $\frac{1}{4}$ " or $\frac{3}{8}$ " thick. One such strip is laid as shown over each "glue-joint" 53 as it is made and passes through the machine. In such case, electrical contact is made with the top of each electrode strip 52 by means of a metal bar in the nature of a "hold down," or a series of such slidably engaging the electrodes as they pass therebeneath. The electrostatic field is set up between the strip electrodes and a table electrode as previously described along which the boards advance and which forms the lower electrode as they are pushed along by strokes of the ram. Such sparking as may occur as the strip contacts the "hold down" metal bar in its skid form, will have no deleterious effect on the wood or glue joint. Preferably each strip electrode 52 is provided with short teeth prongs 54 normal to and projecting therefrom, these prongs or pin points being adapted to be pressed into the wood at either side of the glue line to prevent slipping of the electrode on the wood as the strip elements are advanced beneath the "hold down" skids. Alternatively the electrodes may be provided with a frictional under surface for engaging the wood and preventing slippage on the wood.

The invention in its broader aspects is not limited to the specific steps and procedures and mechanisms shown and/or described but departures may be made therefrom within the scope of the accompanying claims without departing from the principles of the invention and without sacrificing its chief advantages.

What is claimed is:

1. Apparatus for continuous-feed, edge-gluing of strip elements comprising in combination a feed-table; a metal electrode in the table top; a flexible metal electrode overlying said table electrode; a framework carried by said table in vertically adjustable relation thereto; a plurality of members individually, independently supporting said flexible electrode from said framework in vertically adjustable relation thereto; spring members for yieldably opposing upward movement of said supporting members; means for advancing said strip elements along said table slidably between and along said electrodes in firm engagement with a preceding element; and, means for establishing a high-frequency electrostatic field between said electrodes.

2. Apparatus for continuous-feed, edge-gluing of strip elements comprising in combination a table electrode for slidably supporting said elements; means for advancing said elements successively along said table electrode in firm en-

gagement with a preceding element; a flexible sheet metal electrode for slidably engaging the top surface of said elements; a plurality of rail members substantially paralleling the path of movement of said elements in spaced relation to each other and secured to the top surface of said flexible electrode; a framework vertically adjustably carried by said table; rod members extending upwardly from each end of the respective rail members into sliding engagement with said framework; spring means interposed between said framework and said rail members for yieldably resisting upward movement of said rail members; means connected to said rod members for adjusting the spring tension; and, means for establishing a high-frequency electrostatic field between said electrodes.

3. Apparatus for continuous feed edge-gluing of strip elements comprising in combination a flat rigid table support for the work, a pair of high frequency plate electrodes, the lower electrode being embedded in said table support and being flush with the top of the table support, said electrodes each having a substantially plane surface portion in opposing substantially parallel spaced relation to the corresponding plane surfaced portion of the other to provide an elongated passageway through and along which strip elements to be edge glued are adapted to be advanced in edge-to-edge relationship with their upper and lower surfaces in sliding frictional engagement with said opposing plane surfaced portions; means for resiliently urging at least one of

5 said electrodes toward the other to obtain yielding frictional engagement between said strip elements and said electrode portions in transit through said passageway; intermittently operated feed means slidably supported on said table support in alignment with said passageway for advancing said strip elements successively into said passageway in firm engagement with a preceding element; and means for establishing a high-frequency electrostatic field between said electrodes.
